UNITED STATES PATENT OFFICE.

CHARLES A. BICKFORD, OF CHICAGO, ILLINOIS.

FLOORING.

1,282,732.

Specification of Letters Patent.

Patented Oct. 29, 1918.

Application filed July 1, 1918. Serial No. 242,694.

To all whom it may concern:

Be it known that I, CHARLES A. BICKFORD, a citizen of the United States, residing at Chicago, in the county of Cook and State of Illinois, have invented certain new and useful Improvements in Flooring, of which the following is a specification.

My invention relates to metal flooring having interchangeable sections capable of being held in place without separate fastenings and having suitable grooves by which templets, frames or plates may be securely fastened to the floor and against which large and heavy work may be shaped and formed, such as the steel ribs of ships and the like.

To the attainment of these ends and to the accomplishment of other new and useful advantages as will hereinafter appear, my invention consists in the features of novelty 20 in the construction, combination and arrangement of the various parts hereinafter more fully described and claimed and shown in the accompanying drawings wherein,

Figure 1, is a plan view of my improved 25 flooring.

Fig. 2, is an enlarged sectional view of the flooring shown in Fig. 1.

Fig. 3, is a cross section taken on the line A—A in Fig. 2.

Fig. 4, is an irregular cross section taken 30 on the line B—B of Fig. 1.

Fig. 5, is a cross section taken on the line C—C of Fig. 2.

In the construction of my flooring I first 35 provide a series of I beams 10 of suitable dimensions and supporting strength arranged parallel and secured to a suitable foundation or embedded in concrete. I next provide a plurality of standard metal plates 40 11. Each plate is cast with lugs 12 on both sides, which lugs engage the edges or uppermost flanges 13 of the I beams 10. In order to install the metal sections in the flooring structure it is only necessary to slide each 45 section into place by engagement of the lugs of the sections with the upper flanges of the I beams; this connection is close enough so that the sections will slide readily without producing friction or sticking and at the 50 same time tight enough so that the flooring will be firm and the sections will not jar out of place or rattle.

I space the edges of the floor sections apart, both at the end 14 and at the sides 55 15, providing a groove 16, around the four sides of every section; at all of the corners

of these sections I have made the groove 16 to terminate in an enlarged square opening 17. Through the central portion of each of the sections 11, I have provided a series of 60 parallel grooves 18, which run at right angles to the I beams 10, the middle one of the grooves 19, is made shorter than the others and terminates at the center in a square opening 20. Running parallel with 65 the I beams 10, and at right angles to the grooves 18, 19 and 20, I provide another groove 21.

I next provide suitable clamping bolts 22, which may be inserted in the openings 17 and 20, and then slid through any of the 70 grooves 16, 18, 19 and 21, for the purpose of clamping frames, templets, blocks or the like, as at 23, in Fig. 1. This view shows a steel rib bent along a templet line against 75 blocks clamped to the flooring.

It will be apparent that the number arrangement, size and shape of the grooves may be varied indefinitely. I have only shown and described one form and arrangement suitable for standardizing my flooring.

In practice the sections of flooring 11, will be slid against one wall or a steel end strip 24, as shown in Fig. 1; after sufficient numbers of the flooring sections 11, have been 85 placed, a suitable clamping strip 25, may be used at the opposite end bolted or fastened to the I beams by any suitable means as at 26. This will serve to hold the flooring rigidly in place. It will be necessary that 90 at the free end of the flooring, sufficient room be left at all times between the wall and the last row of flooring sections so that the sections may be removed and others replaced in case of breakage or for any other 95 reason.

Since my flooring is composed of a standard design of sectional plates, these plates are interchangeable and may be readily removed or added so as to enlarge or decrease 100 the size of the flooring and replace in case of breakage or for any other reason.

It will be apparent from the foregoing description and the drawings that such a flooring can be made into a rigid platform 105 and secured on cribbing or fastened to vertical steel or wooden scaffolding to form the flooring of a platform on which machine or hand tools may be clamped to facilitate machine operations at considerable elevation 110 above shop or other floors. For example, the face of a steam chest, valve housing and

other similar jobs on large marine engines or heavy machinery may be worked on by available machines or power tools thus eliminating the necessity for constructing special machinery and tools.

5 In cutting steel plates for ships, boilers, tanks, or bridges and in fabricating same, my improved flooring has many obvious advantages to the engineer and mechanic. Fire 10 brick may be laid on my metal flooring and steel plate work, ship's armor and other parts may be readily cut to the required shapes by acetylene cutting equipment used in conjunction with inexpensive guide tools made 15 to engage the slots in my metal flooring. Similar advantages may be had in riveting, punching and welding operations. When not in use for these purposes, these sectional plates provide a durable and smooth floor 20 for workmen to pass over and on which heavy parts may be transported. Other advantages reside in the accuracy and precision of leveling and alining and the facility with 25 which the flooring may be maintained at a low cost at all times. The operating range of motor driven machinery and hand tools may be greatly increased by the use of my flooring whereby such machinery and tools are arranged and clamped in either vertical 30 or horizontal positions or by which the work to be operated on may be clamped to various positions relative to tools and machinery.

While I have illustrated and described certain forms of construction for carrying my invention into effect this is capable of 35

variation and modification without departing from the spirit of my invention, I therefore do not wish to be limited to the precise details of the construction set forth, but desire to avail myself of such variations and 40 modifications as come within the scope of the appended claims.

Having described my invention what I claim as new, and desire to secure by Letters 45 Patent is:—

1. In a structure of the kind described, the combination with suitable supporting means of a plurality of interchangeable floor sections, each having lugs at the sides, and 50 slidably and firmly engaging the supporting means, tongues at the edges of the floor sections spacing them apart and forming grooves; openings at the corners and center of the floor sections and a plurality of 55 grooves in the floor sections.

2. A metal flooring comprising in combination a series of parallel I beams suitably supported; a plurality of interchangeable metal floor sections each section having lugs at the sides and slidably and firmly engaging the upper flanges of the I beams; tongues at the edges of the sections spacing them apart and forming grooves; square openings 60 at the corners and center of the sections; a 65 plurality of grooves in the floor sections and suitable clamping means all as shown and described.

In witness whereof, I hereunto subscribe my name to this specification.

CHARLES A. BICKFORD.

Copies of this patent may be obtained for five cents each, by addressing the "Commissioner of Patents.
Washington, D. C."
